UNITED STATES PATENT OFFICE.

CYRUS L. DANFORTH, OF ST. LOUIS, MISSOURI, ASSIGNOR OF TWO-THIRDS TO CHRISTIAN A. WINDMULLER, STEWART SCOTT, AND J. PETER RICHARZ, OF SAME PLACE.

DESIGN FOR A GLOBE FOR ARC-LAMPS.

SPECIFICATION forming part of Design No. 25,616, dated June 9, 1896.

Application filed January 13, 1896. Serial No. 575,387. Term of patent 14 years.

To all whom it may concern:

Be it known that I, CYRUS L. DANFORTH, of the city of St. Louis, State of Missouri, have invented a new and original Design for a 5 Globe for Are-Lamps, of which the following is a full, clear, and exact description, reference being had to the accompanying drawing, forming a part hereof.

In the drawing the figure is a perspective 10 of a globe for arc-lamps embodying my design.

The essential and distinguishing feature of 15 my design for a globe for arc-lamps is the contrasting shades of color having the outer lines indicated.

1 indicates the hollow body of a globe of my design, the upper end of which is open, as indicated by 2, and the lower end of said body being constructed with an integral de- 20 pending portion 3. The body 1 is circular in

horizontal section and oval in vertical section. The location and outlines of the shades of color which contrast with the color of the body of the globe are shown by the reference-numerals 4 and 5. The contrasting shade of 25 color 4 extends around the lower part of the body 1 in a horizontal line, and the contrasting shades of color 5 are vertically positioned on opposite sides of said body 1, above the contrasting shade 4 and intersecting said contrasting shade 4, and at right angles thereto.

I claim—

The design for a globe for arc-lights, as herein shown and described.

In testimony whereof I affix my signature 35 in presence of two witnesses.

CYRUS L. DANFORTH.

Witnesses:

JOHN C. HIGDON,
MAUD GRIFFIN.
